UNITED STATES PATENT OFFICE.

JOSEPH S. DUNCAN, OF CHICAGO, ILLINOIS, ASSIGNOR TO ADDRESSOGRAPH COMPANY, OF CHICAGO, ILLINOIS, A CORPORATION OF ILLINOIS.

PRINTING MACHINE.

Application filed October 9, 1925. Serial No. 61,416.

This invention pertains to machines employing a plurality of printing devices, each device usually having a particular address. It has been customary to provide a magazine in which a stack of such devices is placed and from the bottom of which the devices are fed one at a time to a position having proper relation to a form from which a circular letter is to be printed. Then the address from the printing device and the letter from the form may be printed at one operation upon a sheet of paper. Machines of this type have been operated either by hand or by motor.

It is one of the principal objects of my invention to provide a machine which is particularly adapted for operation by hand and which shall be of simplified construction having a minimum number of parts therein and which shall at the same time be efficient in operation.

A further object of my invention is to provide novel and improved means for discharging the printing devices after they have been used. It has been customary to permit these devices to slide into an index drawer or tray wherein they are packed by suitable means, the devices passing along a track extending to the drawer or tray. The devices are arranged in the drawer or tray and in case of a large number of such devices being employed there is obviously chance for displacement and jamming thereof particularly when the drawer or tray is nearly empty. By my invention the devices automatically pack themselves in the drawer or hopper in which they are received and into which they drop by their own weight and in proper position.

Still further objects of my invention are to provide novel and improved means for operating the mechanism which feeds the printing devices to and from operative position; for feeding the ribbon by means of which impressions are made from the printing devices and letter forms; for removing the sheets of paper upon which the impressions have been made; for holding the aforesaid paper in position during the time when it is receiving an impression thereon; and for shifting the platen to prevent the formation of grooves therein.

In the accompanying drawings in which

I have shown a selected embodiment of my invention;

Fig. 1 is a plan view of a machine embodying my invention.

Fig. 2 is a front elevation of the machine shown in Fig. 1.

Fig. 3 is a section on the line 3—3 of Fig. 1.

Fig. 4 is a section on the line 4—4 of Fig. 1.

Fig. 5 is a fragmentary plan view of certain of the parts appearing in Fig. 1 and drawn to a larger scale, certain parts being broken away and others omitted for the sake of clearness.

Fig. 6 is a perspective view of one of the printing devices employed with my invention.

Fig. 7 is a section on the line 7—7 of Fig. 5.

Fig. 8 is an end elevation of the structure shown in Fig. 5 as viewed from the left of that figure, certain parts being shown in section.

Fig. 9 is a section on the line 9—9 of Fig. 5.

Fig. 10 is a section on the line 10—10 of Fig. 5.

Fig. 11 is a plan view of certain of the parts appearing in Fig. 1, but with said parts occupying a different position from that shown therein.

Fig. 12 is an end elevation of the structure appearing in Fig. 11, part being shown in section for clearness.

Fig. 13 is a section on the line 13—13 of Fig. 12.

Fig. 14 is a rear view of the greater part of the machine shown in Fig. 1.

Fig. 15 is a section on the line 15—15 of Fig. 14.

Fig. 16 is a section on the line 16—16 of Fig. 14.

Fig. 17 is a section on the line 17—17 of Fig. 14.

Fig. 18 is a section on the line 18—18 of Fig. 14, with the parts shown in a different position from that in which they appear in Fig. 17.

Fig. 19 is a view taken on the line 19—19 of Fig. 14.

Fig. 20 is a plan view of certain mechanism disposed at the rear of the machine as

viewed in Fig. 1, the plane on which this figure is taken being indicated by the line 20—20 of Fig. 14, the mechanism shown in this figure being disposed in the same relative position as in Fig. 1.

5 Fig. 21 is a section on the line 21—21 of Fig. 14.

Figs. 22 and 23 are perspective views of paper gripping mechanism, shown in Figs. 10 17 to 20 inclusive, the two elements shown by these two figures being separated to better show the details of their construction.

Fig. 24 is a fragmentary plan view taken on the line 24—24 of Fig. 14.

15 Referring now to the drawings and more particularly to Figs. 1, 2 and 3, I have shown my invention as embodied in a machine comprising a frame 1 supporting a bed plate 2, upon which is supported the letter form 3.

20 It is common practice to have this form containing a letter which it is intended to send to a number of addresses and for that purpose printing devices carrying address forms are fed successively into position to co-operate with the letter form and then sheets of paper are fed one at a time into position above the letter form and address form after which an impression may be made upon the sheet of paper in a suitable manner and then 25 the printing device carrying the address form is moved from operative position and another is fed into place. In this particular embodiment the impressions are taken from the forms by means of an inked ribbon 4 co-operating with a platen roller 5 mounted on a platen carriage 6 and reciprocated to move the platen back and forth across the paper by means of a suitable handle 7.

I shall now describe the novel and improved means for discharging the printing devices after they have been used, together with the means for operating the mechanism which feeds the printing devices to and from operating position. This structure is best shown in Figs. 1, 3, 5, 7, 8, 9 and 10 40 and referring thereto I have shown at 8 a magazine adapted to contain a plurality of printing devices 9. These devices may be of any suitable construction, but I have shown in Fig. 6 a view of one suitable construction which carries an address form 10 having type 11 thereon forming the address. Beneath the magazine 8 is slidably mounted a carriage 12 carrying a pair of pivoted dogs 13. These dogs are normally held by springs 14 in position to engage the bottom printing device in the magazine, this bottom device resting upon a track formed by the longitudinal members 15 on the stationary bed 16. It will be noted that the sliding carriage 12 is received within suitable guides 17 in the frame, as plainly shown in Figs. 9 and 10.

65 Co-operating with the dogs 13 are a pair of projections 18 fixed to the other end of

the carriage from that on which the dogs are pivoted, the distance between the inner ends of the dogs and the inner faces of the projections being such as to accommodate a printing device therebetween. The carriage 70 is reciprocated on a guide rod 19, by means which will be described more fully in detail later on, upon reciprocation of the platen carriage. The reciprocation of the carriage is from the position shown in Fig. 75 7 beneath the magazine 8 to the position shown in Fig. 3, in which the printing device is deposited upon the bed plate 2'. During this movement the device 9 supported on the carriage passes over the pivoted pawls 20, but upon return movement of the carriage the device is deflected by these pawls on to the track 21 which, as plainly shown in Fig. 9, is formed of a pair of plates supported upon the frame, 80 and is substantially parallel to the track formed by the members 15. This track 21 terminates adjacent a hopper 22 directly beneath the magazine 8 and which, as best shown in Fig. 8, is open from rear to front 85 and is provided with the sides 23 and 23' terminating in shelves 24 and 24' upon which the printing devices may rest.

Extending through the hopper 22 is a receiver 25 having a pair of rests 26 thereon 90 and supported upon a rod 27 pivoted at 28 on the frame of the machine and urged upwardly by the spring 27'. Secured to the top of the rod 27 is the cam 29 co-acting with a cam roller 30 carried by a rod 31 100 slidably supported in brackets 32 and 32' and secured to the side 23 of the hopper. The rod 31 is provided at its forward end with a handle 33 by means of which it may be slid in the brackets within which it is 105 supported, the hopper being provided with a guide rod 22' sliding in the frame of the machine.

The operation of the mechanism described above will be readily understood from the 110 following brief description. The printing devices are taken one at a time from the bottom of a stack of such devices contained in the magazine 8 and fed to position upon the bed plate 2', forming in effect a continuation of the bed plate 2, by means of the dogs 13 on the carriage 12, this movement of the carriage taking place in synchronism with the movement of the platen carriage by 115 means which will be described later. The 120 carriage upon its return movement discharges the printing device which has been used, by engagement of the device with the pawls 20, the device passing along the track 21 and discharging into the hopper 22, this 125 movement along the track 21 being controlled throughout by the projections 18. As a device enters the hopper it is received on the rests 26 and it will be obvious that each device has only a very short distance to drop 130

and there is therefore no chance for it to become displaced and to jam in the hopper. The weight of the accumulating devices in the hopper causes depression of the rests and the rod 27 on which they are mounted to the position shown in dotted lines in Fig. 3, from which it will be apparent that the hopper may be used advantageously with a small number of printing devices or with a relatively large number. When it is desired to empty the hopper the handle 33 may be pulled to bring the hopper forwardly to the position shown in dotted lines in Fig. 3. During this movement the cam roller 30 by its action upon the cam 29 will cause depression of the rod 27 to the dotted line position of Fig. 3, if it is not already there, and consequently the printing devices may be readily removed from the hopper.

20 The above described mechanism exemplifies means for supporting a plurality of printing devices in a hopper at an elevation such that each device entering the hopper has substantially the same distance to drop. Furthermore, the means for handling the devices and feeding them to and from operative position will be seen to be very simple in character and efficient in operation.

I shall now describe the improved mechanism for operating the carriage 12 in synchronism with the operation of the platen carriage. This mechanism is best shown in Figs. 1, 2, 4, 5 and 8 and referring thereto it will be seen that the platen carriage 6 is reciprocated by means of the handle 7 and directed in its movement by suitable guides 34 on the frame of the machine. Secured to the carriage 6 is an operating member 35 moving along a guide 36 on the frame. This operating member 35 has swiveled thereon a block 37. As the platen carriage is moved toward the bed plate 2 from the position shown in Fig. 1, the block 37 slides along a rod 38 passing therethrough

45 and provided at one end with a stop 39 engaging the block 37 to limit movement of the block on the rod. At its other end the rod 38 is provided with an enlarged portion 40 forming a shoulder 41 to engage the block 37 and limit movement of the block in this direction. This end of the rod 38 is pivoted to a link formed with an upper horizontally extending arm 42 and a lower horizontally extending arm 43 connected by a vertical member 44, the entire link being supported on the vertical pivot 42'. The arm 43 is pivoted to a link 45 which in turn is pivoted to a lever 46 fulcrumed at 47 upon the frame of the machine. The member 44 is further provided with an arm 48 co-acting with a stop 49 on the frame to limit movement of the mechanism in one direction. The free end of the lever 46 is pivoted at 50 to a link 51 pivoted to a bracket 52 on the side 55 of the carriage 12. The arm 46 is extended

beyond the pivot 50 as at 53 and co-operates with a stop 54 on the frame to limit movement of the mechanism in the other direction.

The operation of the mechanism just described is evident, but it may be briefly summed up. As the platen carriage is moved from the position shown in Fig. 1 across the bed plate 2 in order to make an impression in the usual manner, the block 37 slides along the rod 38 until it comes in contact with the shoulder 41. This arrangement exemplifies a lost motion connection which permits an extensive movement of the platen carriage without actuation of the carriage 12, which I shall call the feeding device carriage. A printing device is in place upon the bed plate 2', as shown in Fig. 3, before the platen carriage begins its movement, this device having been left in place by the preceding operation. As the block 37 contacts with the shoulder 41 on the rod 38 the linkage is moved from the position shown in Fig. 1 to that shown in Fig. 5. That is, the printing device carriage is moved towards the left, as shown in Figs. 1, 3 and 5 and the printing device is removed from the bed plate 2' and deposited in the hopper 22 in the manner previously described. The carriage 12 obviously slides in the guides 17 and on the guide rod 19 and when it is in the position shown in Fig. 5 it is beneath the magazine 9 and as shown in Fig. 7, the dogs 13 are in a position to catch the next printing device at the bottom of the stack in the magazine. The parts are so arranged that during this forward movement of the platen and its carriage over the bed plate the impression will be taken from the printing device on the bed plate 2' before the block 37 engages the shoulder 41, and in fact the entire impression from both forms, the letter form, and the address form on the printing device, will be made before the carriage 12 is moved.

As the platen carriage is moved back to the position shown in Fig. 1 the block 37 will slide along the rod 38 without causing any movement thereof until it comes in contact with the stop 39, and then further movement of the platen carriage will cause operation of the rod 38, and the linkage will be returned from the position shown in Fig. 5 to that shown in Fig. 1, this causing movement of the printing device carriage from the position shown in Figs. 5 and 7 to that shown in Fig. 3. This movement will cause the delivery of another printing device to the operative position upon the bed plate 2'. Continued reciprocatory movement of the platen carriage by means of the operating handle 7 will cause repetition of this cycle.

I shall now describe the improved means for feeding the inking ribbon 4. This ribbon is wound upon a spool 55 and is adapted

to be unwound therefrom and wound up upon the spool 56, disposed at the opposite end of the bed plate 2 from the spool 55. The mechanism for performing the feeding operation is best shown in Figs. 1, 2, 11, 12 and 13 and referring thereto it will be seen that the cam 57 formed upon the operating member 35 of the platen carriage is adapted to engage a cam roller 58 at the forward limit of travel of the platen carriage. This roller is mounted upon an arm 59 pivoted upon the frame of the machine as at 60 and having pivoted to its lower end a rod 61 reciprocating in a guide 62, this guide being swiveled on the frame and the rod 61 serving to guide the arm 59 in its proper plane and also performing a function which will be described later.

It will be seen that the arm 59 passes close to the spindle 63 upon which is mounted the spool 56, this spindle being journaled in a suitable bracket 64 of the frame, and being provided at its outer end with a knurled handle 65 for manual operation. A similar knurled handle 66 is provided for the spool 55. These knurled handles provide means for winding and rewinding the ribbon which, as shown in Fig. 3, is tensioned over the forms placed on the bed plate, this tensioning being effected by suitable means exemplified by arms 67 and 68 which are pivoted upon the machine frame and bear against the ribbon in a manner well known in the art, and which is illustrated in Fig. 3.

Pivottally connected to the arm 59 is a link 69, pivoted to one end of an arm 70 having its other end loosely journaled on the spindle 63 and being provided with an extension 71 carrying a pawl 72 adapted to co-operate with a ratchet 73, in engagement with which it is held by a spring 74, the ratchet 73 being secured to the spindle 63. It will be obvious that upon actuation of the platen carriage 6 across the bed plate from the position shown in Fig. 1 the cam 57 will cause the arm 59 to rock on its pivot in a counterclockwise direction, as viewed in Fig. 2 and cause the pawl 72 to ride over the teeth on the ratchet 73. As the platen carriage is returned to the position shown in Fig. 1, the arm 59 is rotated in a clockwise direction, as viewed in Fig. 2, by means of the the spring 75, this movement being limited by a suitable stop 76, and the pawl will actuate the ratchet.

The above described mechanism exemplifies means for moving an inking ribbon across the bed plate and above the type carried by the forms on the bed plate, such means being operated by movement of the platen carriage and in an extremely simple and efficient manner.

I shall now describe the improved means for holding the sheet upon which impres-

sions are to be made, in the proper position for making such impressions, and for removing the sheet from impression position. This mechanism is best shown in Figs. 1, 2, 4 and 14 to 24 inclusive, and referring thereto, it will be seen that the rod 61 when actuated by the cam 57 will engage the dog 77, best shown in Fig. 2 and will rock the shaft 78 upon which the dog is secured. The shaft 78 terminates in an arm 79, as plainly shown in Figs. 1 and 14, which rests upon a pin 80 upon a rock arm 81 pivoted at 82 on the frame of the machine and provided with a right angled extension 83, as best shown in Figs. 14, 17, 19, 20 and 24.

Secured to the main frame 1 of the machine is a rod 84, best shown in Figs. 14, 18 and 20 and upon which is slidably mounted an auxiliary frame 85 clamped upon the rod 84 by suitable means 86. Frame 85 is provided with a suitable guide 87, best shown in Figs. 14 and 20 in which is received a roller 88 on the machine frame to co-operate with the rod 84 in maintaining the frame 85 in proper alignment.

Pivoted upon the frame 85 is a rocker 89 comprising a transverse member 90 having a plurality of arms 91 pivoted on the rod 92 and having other arms 93 supporting a transverse rod 94. The transverse member 90 is provided with an arm 95 having at its lower end a roller 96 which rides on the top surface of the extension 83, in contact with which it is held by means of the spring 97.

Pivoted upon the transverse rod 94 is the gripper frame 98 shown in perspective in Fig. 22 and comprising a plurality of gripper fingers 99. The gripper fingers co-operate with means on the auxiliary frame 85 to hold the paper in correct position. This means is exemplified by the structure shown in Fig. 23 and comprises a plurality of surfaces 100 corresponding in number to the gripper fingers 99 and provided with stops 101 against which the edge of a sheet of paper may be placed. The gripper fingers 99 are normally urged into engagement with the surfaces 100 or with a sheet of paper disposed thereon by means of the spring 102. One or more of the gripper fingers is provided with a depending lug 101', which will co-operate with the lugs 101 to properly align the edge of a sheet of paper and will insure that the paper shall not become displaced. Each surface 100 terminates in a depressed portion 103 to permit the gripper fingers 99 to pass beyond and beneath the surface 100, for a purpose which will presently appear.

Mounted upon the platen carriage 6, as best shown in Figs. 14 and 16 and as also indicated in Fig. 17 is a roller 104 supported upon an arm 105 pivoted upon the carriage and held in position by the spring 106 co-operating with the stop 107. This roller

104 is so disposed as to engage and run on a track 108 carried at one end of the gripper frame 98. When the roller 104 is in engagement with the track 108 the gripper frame is raised to the position shown in Fig. 17, for a purpose which will presently appear.

The platen carriage has pivotally mounted thereon a transverse rod 109 to which are secured a plurality of levers 110 having means 111 for securing them in adjusted position on the rod 109. Carried by each lever 110 are one or more fingers 112 adapted to engage the edge of a sheet of paper, but normally held in the raised position shown in Figs. 4 and 17. The upper end of each lever 110 is forked to receive the rod 113 secured to brackets 114 upon a transverse rock shaft 115. The rock shaft 115 is irregular in form, as shown best in Fig. 14, in order to avoid interference with other parts of the machine, which have been omitted in large part for the sake of clearness. The end of the rock shaft shown at the right 25 of Fig. 14 is provided with an arm 116 (see also Fig. 16). Disposed upon the other end of the rock shaft 115 and secured rigidly thereto is a second arm 117. (See Figs. 14 and 15.)

As noted above, the platen carriage is directed in its movement by suitable guides 34 on the frame of the machine. These guides receive rollers 118 upon the platen carriage. Referring particularly to Figs. 2, 35 4, 15, and 16 it will be seen that the platen shaft 119 upon which the platen 5 is secured is revolvably mounted in a pair of arms 120 pivotally mounted at 121 upon the carriage. The platen shaft 119 has secured to each end thereof grooved rollers 122, which receive flanged rollers 123, which flanged rollers are supported upon a shaft 124 carried by links 125 disposed adjacent either end of the shaft. These links 125 are pivotally connected at their other ends to rigid arms 126 upon the rock shaft 115. The rollers 123 contact with an overhead track 127, which limits the upward movement of the rollers, the downward movement thereof being governed by contact with the rollers 122. The platen shaft 119 is urged upwardly by means of springs 128 whereby the rollers 122 and 123 are held in contact and the roller 123 is held in contact with the tracks 127.

The operation of the mechanism just described will be briefly given. The platen carriage 6, as has been stated above, is reciprocated back and forth over the bed plate by means of the handle 7. Assuming that the parts are in the position shown in Figs. 1, 4 and 17, it will be noted that the gripper fingers 99 are raised so as to permit a sheet of paper to be placed against the lugs 101. The opposite edge of the paper will rest 65 upon a plurality of springs 129 and suitable

means (not shown) align the paper in the direction at right angles to the two edges referred to. Now, as the platen 5 moves over to the left, as viewed in Figs. 4 and 17, the roller 104 will leave the track 108 and 70 then the spring 102 will depress the gripper fingers 99 to securely engage the edge of the paper between the fingers 99 and the surfaces 100. The platen continues its travel across the surface of the paper and it 75 will be noted that the fingers 112 will be held in raised position, as shown in Figs. 4 and 17. As the platen carriage approaches the end of its travel and after the platen has left the paper the arm 117 will engage the pin 80 130 on the frame of the machine, this pin being shown in Figs. 1, 14 and 15. This engagement will cause the rock shaft 115 to rotate in a clockwise direction, as viewed in Figs. 15 and 21 and consequently will 85 cause the fingers 112 to be depressed to the position indicated in Fig. 21. Thus it will be seen that upon return movement of the platen carriage the fingers 112 will engage the edge of a sheet of paper, such as 130 90 and tend to carry the paper with it in the return movement.

The paper has been held between the gripper fingers 99 and the surfaces 100, these parts occupying the position shown in Fig. 95 18. However, the platen carriage has, through the cam 57, actuated the dog 77 and rod 78 to depress the rock arm 81, as previously described and the action of the spring 97 has caused the rocker 89 to rotate 100 about its pivot to the position shown in Fig. 19. During this movement the gripper fingers 99 will drag along the paper on the surfaces 100 and pass to the surfaces 103, thus at all times contacting with the paper 105 until the fingers have passed the edge thereof. It will be seen that the fingers 99 are now in a plane beneath that of the paper and as the carriage starts on its return travel the dog 77 is released and the spring 131 will 110 lift the rocker arm 81 and consequently the rocker 89 to the position shown in Fig. 18. During this movement the gripper fingers 99 will pass beneath the edge of the paper and lift the same so that the fingers 112 may pull 115 the paper over the gripper fingers 99 on the return travel of the platen carriage. After the platen carriage has reached its initial position, as shown in Figs. 4 and 17, the rollers 104 will engage the track 108 and 120 lift the gripper fingers to the position indicated in Figs. 4 and 17 when the cycle may be repeated.

When the arm 117 engages with the pin 130 the movement of the rock shaft 115 will 125 cause movement of the shaft 124 and consequently the rollers 123 to the right, as shown in Fig. 15, or to the left as shown in Fig. 16. Then the platen will be raised by the spring 128 out of engagement with the paper. As 130

the platen carriage approaches the initial position shown in Figs. 4 and 17 the arm 116 on the rock shaft 115 will engage the pin 132, best shown in Figs. 1, 14 and 16, and will move the rock shaft back to the position shown in Fig. 16, the contact between the pin 132 and the arm 116 being made on the surface 116' of the arm. This movement will then force the rollers 123 towards the right, as viewed in Fig. 16, or towards the left as viewed in Fig. 15 and will consequently force the platen shaft and the platen down to operative position.

I shall now describe the means for shifting the platen roller axially. This mechanism is designed to avoid the grooving of the platen roller which takes place if it is used continuously with one form. By shifting the platen slightly along its axis after each operation, it is obvious that the type contained on the letter form will not exert pressure against the same portions of the platen as on the preceding operation, when the platen is again operated over the form. By this means the formation of a groove in the platen is avoided and the life thereof is materially increased. The above mechanism is best shown in Figs. 1, 4, 14 and 21 and referring thereto it will be seen that the platen carriage 6 has mounted thereon a rod 133 and secured on this rod between brackets 134 is a sleeve 135, the brackets 134 preventing longitudinal movement thereof. The sleeve is provided at one end with a ratchet 136 co-operating with a pawl 137 pivoted upon an arm 138, which in turn is pivotally mounted upon an auxiliary carriage 139 which supports the platen roller and parts co-operating therewith, as indicated in Figs. 15 and 16. The arm 138 is normally urged upwardly by the compression spring 140 and is provided with a nose 141 bearing against the plate 142 carried by the rock shaft 115. The arrangement of parts is best shown in Fig. 21 and is such that when the rock shaft 115 is actuated to bring the fingers 112 into engagement with a sheet of paper 130, the arm 138 is moved upwardly to the position shown in Fig. 21 by the action of the spring 140, the pawl 137 riding idly over the teeth on the ratchet 136. Then as the rock shaft is actuated to lift the fingers 112 out of engagement with the paper 130, as previously described, and to return the fingers to the position shown in Fig. 4, the arm 138 will be depressed by the contact of the plate 142 with the nose 141 and a rotation of the sleeve 135 will be caused by the action of the pawl upon the ratchet.

Referring now particularly to Figs. 4 and 14, it will be seen that the sleeve 135 is provided with a cam 143 preferably in the form of a cylinder having a spiral cam groove 144 therein. This groove receives a roller 145 secured to the auxiliary carriage 139, Fig. 17.

The operation of the device just described will be apparent, but may be briefly summarized. As just stated above, the sleeve 135 is given a step by step rotation by means of the pawl and ratchet arrangement, best shown in Fig. 21, and it will be obvious that this step by step movement is caused upon each movement of the platen carriage necessary to print one impression from the forms carried by the bed plate. Rotation of the sleeve 75 will cause a longitudinal or axial movement of the auxiliary carriage 139 due to the co-action of the cam 143 and pin 145. It will be noted that the cam groove 144 is continuous and therefore the axial movement of the auxiliary carriage and consequently of the platen roller will be a step by step movement in one direction and then a step by step movement in the opposite direction, the extent of these movements being controlled by the shape of 85 the cam groove 144.

The mechanism just described exemplifies novel and improved means for avoiding the grooving of the platen roller, the disadvantages of which have been set forth above 90 and which are well known in the art. The type of machine with which my invention is used is one in which the same letter form may be used many times and usually is, in the preparation of circular letters, or the 95 like, to be sent out in large quantities. It is therefore obvious that when a platen roller is moved back and forth over the same form several hundred times perhaps, the roller will have grooves formed therein corresponding to the type on the letter form. By my invention this grooving is avoided by a very efficient and at the same time a very simple and easily constructed mechanism. 100

The operation of the entire machine will have become known from the description of the operation of the various parts thereof as given above and it is deemed unnecessary to repeat the same here. It will be obvious that the machine embodies mechanism of novel and greatly improved character for performing the various objects of my invention. 105

I am aware that changes in the form, construction and arrangement of parts may be made without departing from the spirit and without sacrificing the advantages of the invention and I reserve the right to make all such changes as fairly fall within the 110 scope of the following claims. 115

I claim:

1. A printing machine comprising means for printing from a plurality of devices, means for feeding said devices from operative position, and a hopper to receive said devices and comprising pivoted means for supporting them in a stack therein with the top of the stack at a substantially constant elevation. 125

2. A printing machine comprising means for printing from a plurality of devices, means for feeding said devices from operative position, a hopper to receive said devices, and a pivoted receiver disposed in said hopper and capable of downward movement under the weight of the devices resting thereon.

3. A printing machine comprising means for printing from a plurality of devices, means for feeding said devices from operative position, a hopper to receive said devices and comprising pivoted means for supporting them in a stack therein with the top 15 of the stack at a substantially constant elevation, and means to move said hopper to permit removal of said stack of printing devices.

4. A printing machine comprising means for printing from a plurality of devices, means for feeding said devices from operative position, a hopper to receive said devices, a receiver disposed in said hopper and capable of downward movement under the 25 weight of the devices resting thereon, and means to move said hopper to disengage said devices from said receiver.

5. A printing machine comprising means for printing from a plurality of devices, 30 means for feeding said devices from operative position, a hopper to receive said devices, a receiver disposed in said hopper and capable of downward movement under the weight of the devices resting thereon, and means to move said hopper to disengage said devices from said receiver, movement of said 35 hopper causing downward movement of said receiver to bring the devices thereon to the bottom of said hopper.

40 6. A printing machine comprising means for printing from a plurality of devices, means for feeding said devices from operative position, a hopper to receive said devices, a receiver pivoted on said machine and extending into said hopper, and yielding means 45 normally holding said receiver in elevated position and permitting downward movement thereof under the weight of accumulating devices in said hopper.

50 7. A printing machine comprising means for printing from a plurality of devices, means for feeding said devices from operative position, a hopper to receive said devices, a receiver pivoted on said machine and extending into said hopper, yielding means 55 normally holding said receiver in elevated position and permitting downward movement thereof under the weight of accumulating devices in said hopper, and means to move said hopper relatively to said receiver to permit removal of the devices therefrom.

60 8. A printing machine comprising means for printing from a plurality of devices, 65 means for feeding said devices from operative

position, a hopper to receive said devices, a receiver pivoted on said machine and extending into said hopper, yielding means normally holding said receiver in elevated position and permitting downward movement thereof under the weight of accumulating devices in said hopper, means to move said hopper relatively to said receiver to permit removal of the devices therefrom, and means actuated by movement of said hopper to depress said receiver to cause movement of the devices thereon to position at the bottom of said hopper.

70 9. A printing machine comprising means for printing from a plurality of devices, 80 means for feeding said devices from operative position, a hopper to receive said devices, a receiver pivoted on said machine and extending into said hopper, yielding means normally holding said receiver in elevated 85 position and permitting downward movement thereof under the weight of accumulating devices in said hopper, a rod secured to said hopper and having a handle thereon, and cam means on said rod and said receiver 90 and co-operating to cause depression of said receiver upon movement of said hopper by said handle.

10. A printing machine comprising a magazine adapted to contain a plurality of 95 printing devices, a bed plate upon which a printing device is adapted to be placed, a hopper disposed directly beneath said magazine, a carriage reciprocating between said magazine and said hopper and having dogs 100 thereon adapted to feed a device from said magazine to said bed plate and having projections co-operating with said dogs to hold a device therebetween, said dogs feeding said device in one direction of travel of said carriage and said projections feeding said device in the other direction of travel of said carriage.

11. A printing machine comprising a magazine adapted to contain a plurality of 110 printing devices, a bed plate upon which a printing device is adapted to be placed, a hopper disposed directly beneath said magazine, a carriage reciprocating between said magazine and said hopper and having dogs 115 thereon adapted to feed a device from said magazine to said bed plate and having projections co-operating with said dogs to hold a device therebetween, said dogs feeding said device in one direction of travel of said carriage and said projections feeding said device in the other direction of travel of said carriage, pivoted pawls disposed in the line 120 of travel of said carriage and permitting a device on said carriage to pass therover 125 when being fed to said bed plate, but deflecting said device upon return movement of said carriage, and a track to receive said deflected device and guide it to said hopper.

12. A printing machine comprising a 130

magazine adapted to contain a plurality of printing devices, a bed plate upon which a printing device is adapted to be placed, a hopper disposed directly beneath said magazine, a pair of substantially parallel tracks, one of said tracks extending from said magazine to said bed plate and the other from said bed plate to said hopper, and a carriage having means thereon to receive a device from said magazine and feed the same along said first named track to said bed plate and then along said second named track to said hopper.

13. A printing machine comprising a bed plate, a platen carriage having a platen adapted to co-operate with said bed plate, a magazine adapted to contain a plurality of printing devices, a printing device carriage adapted to feed devices to and from position upon said bed plate, and a lost motion connection between said carriages whereby movement of said platen carriage will be independent of movement of said printing device carriage during a part of its operation and will cause movement of said printing device carriage during another part of its operation.

14. A printing machine comprising a bed plate, a platen carriage having a platen adapted to co-operate with said bed plate, a magazine adapted to contain printing devices, a printing device carriage adapted to feed said devices one at a time to and from position on said bed plate, an operating member carried by said platen carriage and having a block swiveled thereon, a rod slidably mounted in said block, means to limit movement of said block on said rod, and a connection between said rod and said feeding device carriage, for the purpose set forth.

15. A printing machine comprising a bed plate, a platen carriage having a platen adapted to co-operate with said bed plate, a magazine adapted to contain a plurality of printing devices, a printing device carriage adapted to feed said devices to and from position on said bed plate, a ribbon co-operating with said printing devices and said platen and adapted to be fed intermittently across said bed plate, a lost motion connection between said carriages, and a cam on said platen carriage and adapted to operate the ribbon feeding mechanism.

16. A printing machine comprising a bed plate, a platen carriage having a platen adapted to co-operate with said bed plate, a magazine adapted to contain a plurality of printing devices, a printing device carriage adapted to feed said devices to and from position on said bed plate, a ribbon co-operating with said printing devices and said platen and adapted to be fed intermittently across said bed plate, a lost motion connection between said carriages, and a cam on one of said carriages to feed said ribbon.

17. A printing machine comprising a bed plate, a platen carriage having a platen adapted to co-operate with said bed plate, a ribbon stretched over said bed plate and wound upon spools on either side thereof, a ratchet on one of said spools, a pawl co-operating with said ratchet, an arm mounted adjacent said spool and having a cam roller thereon, and a cam on said platen carriage and contacting with said roller to operate said ratchet.

18. A printing machine comprising a bed plate, a clamp for holding paper in position above said bed plate, a platen carriage having a platen adapted to co-operate with said bed plate, means to release said clamp and operated by movement of said platen carriage.

19. A printing machine comprising a bed plate, means for holding a sheet of paper in position above said bed plate and comprising a surface upon which the edge of said paper rests and a gripper finger co-operating with said surface to clamp said paper in position, a platen carriage having a platen adapted to co-operate with said bed plate, and means operated by the movement of said platen carriage to slide said gripper finger in respect to said surface and beyond the edge of the paper thereon.

20. A printing machine comprising a bed plate, means for holding a sheet of paper in position above said bed plate and comprising a surface upon which the edge of said paper rests and a gripper finger co-operating with said surface to clamp said paper in position, a platen carriage having a platen adapted to co-operate with said bed plate, and means operated by the movement of said platen carriage to slide said gripper finger in respect to said surface and beyond the edge of the paper thereon and to slide said gripper finger back under the edge of said sheet of paper.

21. A printing machine comprising a bed plate, means for holding a sheet of paper in position above said bed plate and comprising a surface upon which the edge of said paper rests and a gripper finger co-operating with said surface to clamp said paper in position, a platen carriage having a platen adapted to co-operate with said bed plate, and means operated by the movement of said platen carriage to slide said gripper finger in respect to said surface and beyond the edge of the paper thereon and to slide said gripper finger back under the edge of said sheet of paper and then to lift the edge of said sheet of paper to remove it from said bed plate.

22. A printing machine comprising a bed plate, means for holding a sheet of paper in position above said bed plate and comprising a surface upon which the edge of said paper rests and a gripper finger co-

operating with said surface to clamp said paper in position, a platen carriage having a platen adapted to co-operate with said bed plate, a cam on said platen carriage, 5 and means operated by said cam at one end of the movement of said platen carriage across said bed plate to operate said gripper finger.

23. A printing machine comprising a bed plate, means disposed at one edge of said bed plate to hold a sheet of paper, a platen carriage having a platen adapted to co-operate with said bed plate, and means disposed at the opposite side of said bed plate 10 from said holding means and operated by said platen carriage to release said holding means.

24. A printing machine comprising a bed plate, means disposed at one edge thereof for holding a sheet of paper comprising a surface upon which the edge of a sheet is adapted to rest and a gripper finger co-operating with said surface, a platen carriage having a platen adapted to co-operate 20 with said bed plate, a pivoted gripper frame carrying said finger and adapted to be rocked on its pivot by said platen carriage, a rocker supporting said gripper frame, and means to actuate said rocker and operated 30 by said platen carriage when it approaches the opposite edge of the bed plate from said first named edge.

25. A printing machine comprising a bed plate, a platen carriage having a platen 35 adapted to co-operate with said bed plate, means to hold a sheet of paper above said bed plate and comprising a surface on which said sheet of paper is adapted to rest and a gripper finger adapted to co-operate with 40 said surface, said holding means being disposed at one edge of said bed plate, a pivoted gripper frame carrying said gripper finger and held in position to release said sheet of paper by said platen carriage when 45 at the said side of the bed plate, a rocker supporting said gripper frame, means extending beneath said bed plate to actuate said rocker, and means disposed at the opposite side of said bed plate from said first 50 named side to operate said rocker actuating mechanism and in turn operated by movement of said platen carriage to said opposite side of said bed plate, operation of said rocker causing said gripper finger to slide beyond the edge of the sheet of paper 55 and then to slide back beneath said edge, and return of said platen carriage to the first named side of said bed plate causing said finger to rise and thus raise the edge of said sheet.

26. In a printing machine, means to hold a sheet of paper and comprising a surface upon which the edge of said sheet may be placed, a gripper finger adapted to co-operate with said surface to hold said sheet, 60

means to slide said finger beyond said edge, means to slide said finger back beneath said edge, and means to raise said finger to lift said sheet.

27. In a printing machine, means to hold 70 a sheet of paper and comprising a surface upon which the edge of said sheet may be placed, a gripper finger adapted to co-operate with said surface to hold said sheet, means to slide said finger beyond said edge, 75 means to slide said finger back beneath said edge, means to raise said finger to lift said sheet, and means engaging the opposite edge of said sheet to pull the same over said finger.

28. A printing machine comprising a bed plate, a plurality of springs adjacent one edge thereof and adapted to maintain the edge of a sheet of paper in position above 80 said bed plate, a platen carriage having a platen adapted to co-operate with said bed plate, a plurality of fingers pivotally mounted on said carriage and adapted to engage the edge of said sheet above said springs, for the purpose set forth.

29. A printing machine comprising a bed plate upon which a sheet of paper is adapted to be placed, a platen carriage having a platen adapted to co-operate with said bed plate, a plurality of fingers pivotally mounted upon said carriage and adapted to engage an edge of said sheet, and means to raise and lower said fingers upon movement of said carriage back and forth over said bed plate, said fingers being raised out of engagement with said paper when said platen is making an impression and being lowered into engagement with an edge of said paper upon return movement of said carriage.

30. A printing machine comprising a bed plate, means to hold a sheet of paper in position on said bed plate, a platen carriage having a platen adapted to co-operate with said bed plate, a printing device carriage adapted to feed printing devices into position on said bed plate, a ribbon stretched above said bed plate and adapted to be fed intermittently thereover, an operating member on said platen carriage and having a lost motion connection with said printing device carriage and a cam on said operating member and adapted to operate said ribbon feeding mechanism and said paper holding means.

31. A printing machine comprising a bed plate, means to hold a sheet of paper in position on said bed plate, a platen carriage having a platen adapted to co-operate with said bed plate, a printing device carriage adapted to feed printing devices into position on said bed plate, a ribbon stretched above said bed plate and adapted to be fed intermittently thereover, means to shift said platen on its carriage, and means controlled 125

by movement of said platen carriage to operate said printing device carriage, said ribbon feeding mechanism, said paper holding means and said platen shifting means.

32. A printing machine comprising a bed plate, means to hold a sheet of paper in position on said bed plate, a platen carriage having a platen adapted to co-operate with said bed plate, a printing device carriage adapted to feed printing devices into position on said bed plate, a ribbon stretched above said bed plate and adapted to be fed intermittently thereover, means to shift said platen on its carriage, and means controlled by movement of said platen carriage to operate said printing device carriage, said ribbon feeding mechanism, said paper holding means and said platen shifting means, and to raise and lower said platen in respect to said bed plate.

33. A printing machine comprising a bed plate adapted to receive a sheet of paper, a platen carriage having a platen adapted to co-operate with said bed plate, a plurality of fingers on said carriage and adapted to contact with an edge of said sheet to remove it from said bed plate, means to rock said fingers and to raise and lower said platen in unison, said fingers being raised and said platen being lowered during movement of said carriage over said bed plate in one direction and said platen being raised and said fingers being lowered during the return travel of said carriage over said bed plate.

34. A printing machine comprising a bed plate upon which a sheet of paper is adapted to be placed, a platen carriage having a platen adapted to co-operate with said bed plate, a plurality of fingers on said carriage and adapted to engage an edge of a sheet of paper, a rock shaft on said carriage, means to actuate said rock shaft to lower said fingers at the end of the travel of said carriage in one direction, and means to actuate said rock shaft to raise said fingers at the end of the travel of said carriage in the opposite direction.

35. A printing machine comprising a bed plate upon which a sheet of paper is adapted to be placed, a platen carriage having a platen adapted to co-operate with said bed plate, a plurality of fingers on said carriage and adapted to engage an edge of a sheet of paper, a rock shaft on said carriage, means to actuate said rock shaft to lower said fingers at the end of the travel of said carriage in one direction, and means to actuate said rock shaft to raise said fingers at the end of the travel of said carriage in the opposite direction, said lowering and raising of said fingers being accompanied by raising and lowering respectively of said platen in respect to said bed plate.

36. A printing machine comprising a bed plate upon which a sheet of paper is adapted to be placed, a platen carriage having a platen adapted to co-operate with said bed plate, a plurality of fingers on said carriage and adapted to engage an edge of a sheet of paper, a rock shaft on said carriage, means to actuate said rock shaft to lower said fingers at the end of the travel of said carriage in one direction, means to actuate said rock shaft to raise said fingers at the end of the travel of said carriage in the opposite direction, and means operated by movement of said rock shaft to shift said platen on said carriage.

37. A printing machine comprising a bed plate, a platen carriage having a platen adapted to co-operate with said bed plate, and means to shift said platen axially in respect to said carriage after each operation thereof.

38. A printing machine comprising a platen carriage having a platen roller thereon, means for reciprocating said carriage, and means actuated by said reciprocation to move said platen intermittently lengthwise of its axis.

39. A printing machine comprising a bed, a main carriage adapted to be reciprocated over said bed, an auxiliary carriage carried by the main carriage and movable conjointly with and independently of the main carriage, and a platen roller carried by said auxiliary carriage.

40. A printing machine comprising a bed plate, a main carriage adapted to be reciprocated over said bed plate, an auxiliary carriage carried by and movable relatively to the main carriage, a platen roller on said auxiliary carriage, and means for intermittently moving the auxiliary carriage and the platen roller lengthwise of the platen roller.

41. A printing machine comprising a bed plate, a platen carriage adapted to be reciprocated across said bed plate, an auxiliary carriage on said first named carriage and capable of movement at right angles to the direction of movement across said bed plate, a platen roller on said auxiliary carriage, a cylindrical cam having a peripheral groove therein and rotatably supported on said platen carriage, means received in said groove and rigid with said auxiliary carriage, a ratchet rigid with said cam, and a pawl on said platen carriage and operated at the end of the movement of said carriage in one direction, for the purpose set forth.

42. A printing machine comprising a bed plate, means to hold a sheet of paper in position on said bed plate, a platen carriage having a platen adapted to cooperate with said bed plate, a printing device carriage adapted to feed printing devices into position on said bed plate, a ribbon stretched

above said bed plate and adapted to be fed intermittently thereover and means controlled by movement of said platen carriage to operate said printing device carriage, said ribbon feeding mechanism and said paper holding means.

43. A printing machine comprising a bed

plate, a platen carriage having a platen adapted to co-operate with said bed plate, and means to shift said platen in respect to 10 said carriage after each operation thereof, and to lift said platen in respect to said bed plate.

JOSEPH S. DUNCAN.
